UNITED STATES PATENT OFFICE.

LEMUEL B. SAWYER, OF BOSTON, MASSACHUSETTS.

CHECK-VALVE FOR SOIL-PIPE VENTILATORS.

SPECIFICATION forming part of Letters Patent No. 340,157, dated April 20, 1886.

Application filed October 19, 1885. Serial No. 180,300. (No model.)

To all whom it may concern:

Be it known that I, LEMUEL B. SAWYER, of Boston, (Jamaica Plain,) in the county of Suffolk and State of Massachusetts, have invented 5 a new and useful Check-Valve for Soil-Pipe Ventilators, of which the following, taken in connection with the accompanying drawings, is a specification.

In most cities which have a system of under- 10 ground sewers with which the house-drains connect, the owners of buildings which are provided with sinks and water-closets which discharge into drains connected with the sewers, are required to carry the soil-pipes 15 through the roof of the building and some distance above the same, and to trap their drains between the building and the sewer, all for the purpose of preventing sewer-gas from entering the rooms of the building and 20 ventilating the drains and soil-pipe by conveying the foul odors to the open air above the top of the building. It has been found, however, that this ventilating pipe does not 25 ventilate to any considerable extent, unless air is admitted to the drain or soil pipe at or near its lowest point, as the air in said pipe will remain as dead air if one end of the pipe is closed, and hence it has become common to insert a short stand-pipe into the drain out- 30 side of the building and between it and the trap, the upper end of said stand-pipe being open to the air just above ground. By this arrangement a current of air will be kept moving through the drain and soil-pipe from 35 the end of said short stand-pipe to the discharge of the soil-pipe above the roof of the building, and perfect ventilation will result, except as hereinafter stated.

Whenever the contents of the pan of a water- 40 closet are dumped into the soil upon the second, third, or fourth floors of the building, the mass of matter falling through the soil-pipe to the horizontal drain acts as a piston to force all the air or gas below it toward the 45 sewer, and as it can escape through the short stand-pipe above referred to easier than it can through the trap into the sewer, the foul gases are forced through said stand-pipe into the open air, perhaps directly beneath the parlor- 50 window, creating for the time being a great nuisance.

To abate this nuisance and at the same time

retain the proper circulation of air through the drain and soil pipe is the object of my invention; and it consists in a check-valve applied to the end of said stand-pipe, constructed and arranged to be closed substantially air-tight whenever there is a back-pressure to force the body of air in the drain toward the sewer and to be opened again automatically when said back-pressure is removed.

It further consists in certain novel features of construction, arrangement, and combination of parts which will be readily understood by reference to the description of the drawings, and to the claims to be hereinafter given.

Figure 1 of the drawings is an elevation of my check-valve with a portion of the hood or shield and of the pipe for coupling it to the stand-pipe broken away. Fig. 2 is a central vertical section of the same, cutting through two of the air-passages and valves. Fig. 3 is an elevation of a portion of one of the valves and illustrating the manner of hanging the same, and Fig. 4 is a vertical section of one wall of a building and illustrating the arrangement of the drain, soil-pipe, and stand-pipe with my check-valve applied thereto.

In the drawings, A is the wall of the building; A', A², A³, and A⁴, the several floors thereof; C, the drain provided with the trap C'; D, the soil-pipe; E, the stand-pipe, and F, F', F², and F³ represent water-closet bowls.

My check-valve consists of a flat-sided 85 casing, G, made preferably hexagonal or octagonal and secured at its lower end to the ring H, provided with the short pipe H', to enter the stand-pipe E and support the casing in position. The upper end of the casing G has 90 formed thereon the outwardly-projecting flange a, to the upper side of which is secured the flange b of the inverted cone I, as shown. The outer edge of the flange a of the casing G is provided with the upwardly-projecting 95 annular lip c, which fits the interior of the cylindrical portion of the hood J, and to which said hood is secured by the screws c' c', as shown. The casing G has formed in one or more of its sides an air passage or port, d, 100 through which air may enter the stand-pipe E and rise through the soil-pipe D and be discharged from its upper end by virtue of the draft in that direction caused by the greater

altitude of the end of the soil-pipe above the end of the stand-pipe.

5 *e e* are clapper-valves, made of thin light material and pivoted at their lower end, as shown in Fig. 3, to the interior of the casing G, and constructed and arranged to fall away from the openings or ports *d* whenever the outward pressure is removed, and to automatically close said ports whenever the air attempts to escape through said ports.

10 *g g* are adjustable stops to limit the distance to which the valves *e e* shall open.

15 The operation of my invention is as follows: So long as no water-closet is being used, the valves *e e* remain open, as shown in Fig. 2, and a current of air is constantly passing down the pipe E, along the drain-pipe C, up the soil-pipe D, and being discharged from the upper end of soil-pipe D, but the moment a pan of one 20 of the closets is dumped and its contents discharged into the soil-pipe D, the upward current of air and gases is checked and forced in the opposite direction, thus causing a current of air and gases up the stand-pipe E, which, 25 being deflected by the inverted cone I, impinges upon and closes the valves *e e*, thus effectually preventing the escape of foul gases and odors, and the discharge is forced into the trap. As soon as the discharge has reached 30 the drain and spread itself along its bottom, the outward pressure upon the valves *e e* ceases and said valves open, and the normal condition of the circulation is restored. The cylindrical portion of the hood J extends 35 downward to or below the bottom of the air-

passages *d*, to prevent snow and ice accumulating in said passages and preventing the action of the valves, and also to prevent high winds from injuriously affecting the operation of the valves.

40

What I claim as new, and desire to secure by Letters Patent of the United States, is—

1. In combination with the drain-pipe C, the soil-pipe D, and the stand-pipe E, a perforated valve-casing, a series of pivoted valves 45 and adjustable stops for regulating the extent of opening to be given to the valves, substantially as described.

2. In combination with the drain-pipe C, the soil-pipe D, the stand-pipe E, the perforated casing, and pivoted valves, the inverted conical deflector extending downward below the valves, substantially as and for the purposes described.

50

3. In combination with the drain-pipe C, 55 the soil-pipe D, the stand-pipe E, the perforated casing, and pivoted valves, the hood inclosing the upper portion of said casing and extending downward to the bottom of the openings in said casing, substantially as and 60 for the purposes described.

In testimony whereof I have signed my name to this specification, in the presence of two subscribing witnesses, on this 12th day of October, A. D. 1885.

LEMUEL B. SAWYER.
